CLAIM

The ornamental design for a refuse container for animal waste, as shown and described.

DESCRIPTION

FIG. 1 is a front elevational view of a refuse container for animal waste embodying my new design;

FIG. 2 is a right side elevational view thereof;

FIG. 3 is a right side elevational view with the lid in an open position;

FIG. 4 is a bottom plan view thereof;

FIG. 5 is a top plan view thereof; and,

FIG. 6 is a top plan view with the lid in the open position.

The circle on the front of the body of the container in

FIG. 1 is an aperture. The rear and left sides of the body of the container are the same as the right side shown in FIGS. 2 and 3.
